UNITED STATES PATENT OFFICE.

HAROLD A. COLBY, OF WAUKEGAN, ILLINOIS.

BUTT GAUGE.

Application filed October 23, 1925. Serial No. 64,442.

This invention relates to gauges, and more particularly to a butt gauge especially adapted for use in applying hinge butts to doors and door frames.

5 One of the main objects of the invention is to provide a tool of simple and inexpensive construction which may be used as a butt gauge for applying hinge butts, though it may also be used for other purposes. Another 10 object is to provide a tool of this character by means of which a door or the jamb of a door frame can be readily marked to indicate the width and the depth of the cut or recess to be made for the reception of a hinge butt. Further objects will appear from the detailed description.

In the drawings:

Fig. 1 is an outer face view of the gauge.

Fig. 2 is an inner face view.

20 Fig. 3 is an edge view.

Fig. 4 is a section taken substantially on line 4—4 of Fig. 2.

Fig. 5 is a section taken substantially on line 5—5 of Fig. 2.

25 The gauge includes a main plate 1 provided at one end with a right angularly disposed flange 2 and at its other end with a right angularly disposed flange 3 which is directed oppositely to flange 2. A carriage 4 is slidably mounted on plate 1 on the face thereof beyond which flange 3 projects. This carriage is secured in adjustment by means of a thumb nut 5 which threads onto a threaded stud 6 extending from the body 7^a 30 of an adjustable member 7. Stud 6 extends through a rib 8 formed on the outer face of carriage 4 and fits snugly in a slot 9 which extends longitudinally of plate 1 and terminates a short distance from each end thereof.

40 At the end of the carriage disposed toward the flange 3, a flange 10 is provided. On the opposite end of the carriage are walls 11 which converge to form a right angle with respect to each other, and which are disposed 45 at 45° angles with respect to the longitudinal edges of the main plate 1.

Flange 3 is bevelled at each end thereof to produce a relatively sharp marking edge 3^a and flange 10 is oppositely bevelled at each 50 end to provide a marking edge 10^a. In using the device for marking a door or the jamb of a door casing for the width of a hinge butt, a carriage 4 is adjusted along the plate 1 so that the distance between the flanges 3 and 10 corresponds to the width of the hinge 55 butt to be applied. After this has been done

the device is moved along the door or the door jamb, as the case may be, with one of the flanges in contact with the door or the jamb, the other flange being used to mark the door or jamb at a distance from the edge thereof corresponding to the width of the hinge butt to be applied.

For marking the depth to which the material of the door or jamb is to be removed to accommodate the hinge butt, I provide a slide 11' having a slot 12 which receives a threaded stud 13 extending from the body 7^a of member 7. A thumb nut 14 is threaded on stud 13 and coacts with body 7^a of member 7 for securing the slide in adjustment transversely of carriage 4. The slide is provided with a downwardly directed flange 15 disposed at right angles to the slide and having a thickened portion 16 which bears against the outer face of flange 10 and coacts therewith to hold the slide in proper alignment with the flange. The slide 11 is provided with a reduced portion 11^a which operates between flange 10 and the adjacent flange 11 of carriage 4. A marking point 17 extends from the outer end of flange 15 and is disposed at right angles thereto, this point being directed toward flange 10. Slide 11' is adjusted so that the distance between the adjacent lateral edge of plate 1 and point 17 corresponds to the thickness of the hinge butt to be applied, after which the gauge is positioned with the edge of plate 1 in contact with the marked surface of the door or jamb and with point 17 pressed into the wood of the door or jamb. The plate is then moved along the door or jamb casing so the point 17 may engrave a line indicating the depth to which the material of the door or jamb should be removed. In this manner the width as well as the depth of a cut to be made to accommodate a hinge butt can be readily indicated thus effecting a material saving in time in applying hinge butts to door and the jambs of door frames.

For convenience, the face of plate 1 at which thumb nut 5 is positioned can be graduated as illustrated in Figure 1, the graduations being used with reference to the outer end 8^a of rib 8 and indicating the distance between the flanges 3 and 10. The scale of graduations facilitates use of the device when the width of the hinge butts to be applied is known.

While this invention is intended for use more particularly as a butt gauge it may

also be used for other purposes, such as marking lines at angles of 45 degrees, as previously stated. The flange 2 is disposed at right angles to plate 1 transversely thereof so that, by engaging this flange over the edge portion of a board or other work to be operated upon, the lateral edges of plate 1 can be employed as straight edges for drawing lines at right angles to a board or other work to be cut or operated upon.

As illustrated in Figure 5, the inner face of flange 10 may be provided with suitable graduations which are to be used with reference to the inner end of slide 11' to facilitate use of the marking point 17 when the thickness of the hinge butts to be used is known.

What I claim is:

1. In a device of the class described, an elongated plate provided at one end with a transversely extending flange, said plate being further provided with a longitudinally extending slot, a carriage slidably mounted on the plate and provided with a rib snugly fitting into said slot, said carriage having a flange disposed in parallelism with the flange of the plate, a member including a body provided with a stud extending through the carriage and the rib thereof, a thumb nut threaded on said stud and co-acting with said body for securing the carriage in adjustment longitudinally of the

plate, the body of said member being provided with another stud, a member having a slot receiving said second stud at the other end of the body, said last mentioned member being confined between said second stud and the flange of the carriage and being movable transversely of the carriage, and a thumb nut threaded on the second mentioned stud co-acting with the body for securing the movable member in adjustment, said movable member being provided at one end with a marking element.

2. A marking tool including an elongated rectangular base plate having a slot formed longitudinally therein and having a flange thereon, said base plate having graduations thereon, a carriage plate slidable on said base plate and having a rib thereon disposed in said slot, a flange portion on said carriage plate parallel with the flange on said base plate, a stud member for adjustably securing said carriage and said base plate, and a member having an elongated slot and provided with a marking element adapted for adjustment transversely to said base plate, said stud member providing means for securing said last mentioned member independently of the carriage plate.

In testimony whereof I affix my signature.

HAROLD A. COLBY.
